UNITED STATES PATENT OFFICE.

DAVID J. MORROW AND JOHN C. MORROW, OF PEORIA, NEW YORK.

BEAN-HARVESTER.

SPECIFICATION forming part of Letters Patent No. 717,435, dated December 30, 1902.

Application filed April 19, 1902. Serial No. 103,702. (No model.)

To all whom it may concern:

Be it known that we, DAVID J. MORROW and JOHN C. MORROW, citizens of the United States, residing at Peoria, in the county of Wyoming and State of New York, have invented a new and Improved Bean-Harvester, of which the following is a specification, reference being had to the accompanying drawings, in which—

10 Figure 1 is a top or plan view of one of our bean-harvesters with the seat removed; and Fig. 2 is a left-hand side view of such a machine with the wheel toward the observer removed and with the handles for raising and 15 lowering the harvester, as well as part of the mechanism for operating the gathering-rake by power, removed, and showing also only the handle used to operate the gathering-rake, which constitutes one of the essential features 20 of our present invention. Fig. 3 is a detail view of part of the mechanism used for operating the gathering-rake by power, such view taken from the right-hand side of the machine. Fig. 4 is a detail view showing the method of 25 supporting crank-shaft (or tube) r^3 from the cross-piece a^6 . Shaft (or tube) r^3 is similarly supported from cross-piece a^5 . Fig. 5 is a detail view similar to Fig. 3, showing the method of supporting the gears g^2 and g^3 on 30 shaft r' and stud r^4 , respectively, by means of block a^7 from cross-piece a^3 . Fig. 6 shows in detail view the support and connection of handle h to crank-shaft r and the support for such shaft from cross-piece a' . This crank- 35 shaft r receives a similar support from cross-piece a^2 . Figs. 7 and 8 are detail views showing the support of handle h^2 on shaft r^5 and also the train of mechanism by means of which it operates to tilt the frame of the ma- 40 chine relatively to the tongue T. Fig. 9 shows in detail view the support and connections of handle h^3 to crank-shaft (or tube) r^3 .

The object of our invention is to provide a hand or power operated gathering-rake for a 45 bean-harvester that shall operate to gather the beans as they are harvested into bundles, so that they may be readily handled with a fork.

Similar letters refer to similar parts through 50 out the several views.

Referring to the accompanying drawings,

w and w' are the wheels of the bean-harvester, having the usual swinging crank-axes r and r^3 , working in bearings secured to the under side of the cross-pieces a' , a^2 and a^5 , a^6 , as seen 55 in Figs. 4, 6, and 9, for cross-pieces a' and a^6 . The axle of the wheel w is a plain crank-axe 60 r , as indicated in the drawings, while the axle of the wheel w' consists of a pin supported by the crank s^2 , rigidly secured to the tube r^3 , 65 while such tube is suitably supported in bearings from the under side of cross-pieces a^5 and a^6 , as indicated in Figs. 4 and 9, for cross-piece a^6 . The hub of the wheel w' has rigidly secured to it a gear g , which meshes with a 70 second gear g' , and such gear g' is rigidly secured to a shaft r' , revolvably supported in the tube r^3 , and a bearing on the under side of the cross-piece a^3 , all operating as will be described. These cross-pieces a' , a^2 , a^3 , a^5 , 75 and a^6 , as well as another somewhat similar piece a^4 , are secured at their front and rear ends, respectively, to the base-pieces b' and b^2 .

The tongue T is pivoted between the front ends of the cross-pieces a^3 and a^4 , and a handle 75 h^2 is provided, by means of which the outer or forward end of this tongue T may be, through the usual mechanism, as shown in Figs. 7 and 8, raised or lowered as desired. Handles of the usual construction h and h^3 80 and operating in substantially the usual way are provided for raising and lowering the frame of the harvester by turning the shaft r and the tube r^3 , respectively, all as indicated in Figs. 6 and 9.

Extending downward from the frame-pieces are seen the usual cutters h and h' , having the usual gathering-tines i i' secured just above these cutters.

A shaft r^2 , working in bearings secured on 90 the upper sides and at the rear ends of the cross-pieces a' , a^2 , a^3 , a^4 , a^5 , and a^6 , has secured thereon a series of cranks or arms c , with their rear ends all connected by the plate e , while the gathering-teeth t extend through 95 this plate e and the rear end of the arms c bent at right angles with the body portions thereof, so as to lie parallel with the plate e in such a way that the two nuts seen at the front ends of the teeth t serve to secure these 100 teeth firmly in the position indicated.

A crank s , secured upon the shaft r^2 , has

- articulating with the upper end thereof a connecting-rod d , the front end of which articulates, as indicated in Fig. 2, with the lower end of the tilting lever h' , pivoted at p' .
- 5 On the inner end of the shaft r' a gear g^2 is secured, and meshing with this gear g^2 , as seen in Figs. 1 and 3, is a gear g^3 , revoluble upon the stud r^4 , having a suitable rigid support a^7 secured on the under side of the cross-piece a^3 . The means for supporting the gears g^2 and g^3 from the cross-piece a^3 is seen in Fig. 5. This gear g^3 carries a pin p , which forms a crank to engage when desired the opening in the front end of the connecting-rod v , as seen in Fig. 3. There is secured to the shaft r^2 , besides the crank s , a crank s' , to which the rear end of this connecting-rod v is pivoted. This connecting-rod v is normally held out of engagement with the crank-pin p by the 20 spring f' , secured, as seen in Fig. 3, to the cross-piece a^3 . The cross-piece a^3 also supports a spring-plate f , which carries at its free and upper end, as seen in Fig. 3, a roller w^2 . The spring f is so proportioned and the 25 roller w^2 is so situated that when the operator places his foot upon the upper end of such spring f and depresses it the roller w^2 depresses the connecting-rod v , thereby causing the pin p as it is revolving to engage such rod v , and thus to raise the teeth t . The roller w^2 permits the rod v to move beneath it and also permits the operator to follow up the rod with the spring f to insure that the rod v and pin p shall remain in engagement until the 30 rod v strikes the pin p^2 , secured to the cross-piece a^3 , at which time the desired amount of upward motion of the teeth t is effected, and they may be then released from the operating mechanism.
- 35 40 The operator in using our harvester after adjusting the cutters at the proper height by means of the handles h and h^3 lowers the teeth to the position indicated in full lines in Fig. 2, and after a sufficient quantity of the bean-stalks have accumulated beneath and in front of the teeth t the spring f is depressed by the operator, causing the teeth to occupy the position indicated in dotted lines, as already described, and discharging the bean-stalks beneath them in a bunch. This process may be repeated as often as a suitable quantity of the bean-stalks has accumulated on the teeth. If, as often happens, it is desired to raise the teeth by hand or to hold them in their raised 45 50 55 position longer than they would be if the power apparatus were used, the operator draws the handle h' toward him, and by holding it in that position causes the teeth to remain in their upper position as long as he may desire.
- 60 65 When for any reason the teeth have a tendency to rise or jump, so as not to do their work properly, the operator may hold them firmly in their working position by pushing the handle h' away from him.
- 65 In the process of gathering the stalks by the

teeth t a large quantity of stones and dirt is removed.

What we claim is—

1. In a bean-harvester, in combination with the wheels and a frame supporting the cutters thereof, vertically-adjustable mechanism for supporting such frame from such wheels, a rake having a series of teeth extending to the rear of such cutters and pivoted to such frame, and connections between one of the wheels of such harvester and such rake whereby, independently of the adjustment of such frame, when desired, the rotation of one of such wheels may be caused to operate such rake. 75

2. In a bean-harvester, in combination with the wheels and a frame supporting the cutters thereof, vertically-adjustable mechanism for supporting such frame from such wheels, a rake having a series of teeth extending to the rear of such cutters and pivoted to such frame, 80 connections between one of the wheels of such harvester and such rake whereby, independently of the adjustment of such frame, when desired, the rotation of one of such wheels may be caused to operate such rake, and also 85 an operating-handle and connections between such handle and such rake whereby the movement of such handle operates such rake as desired. 90

3. In a bean-harvester, in combination with the wheels and a frame supporting the cutters thereof, crank-axes for supporting such frame from such wheels, means for adjusting such frame on such crank-axes, a rake having a series of teeth extending to the rear of such cutters and pivoted to such frame, and connections between one of the wheels of such harvester and such rake whereby, independently of the adjustment of such frame on such crank-axes, when desired, the rotation of one 95 of such wheels may be caused to operate such rake. 100

4. In a bean-harvester, in combination with the wheels and a frame supporting the cutters thereof, crank-axes for supporting such 110 frame from such wheels, means for adjusting such frame on such crank-axes, a rake having a series of teeth extending to the rear of such cutters and pivoted to such frame, connections between one of the wheels of such harvester and such rake whereby, independently of the adjustment of such frame on such crank-axes, when desired, the rotation of one 115 of such wheels may be caused to operate such rake, and also an operating-handle and connections between such handle and such rake 120 whereby the movement of such handle operates such rake.
